(57) **CLAIM**

The ornamental design for an input/output module, as shown and described.

DESCRIPTION

FIG. 1 is a perspective view of an input/output module; FIG. 2 is a front view of the input/output module; FIG. 3 is a rear view of the input/output module; FIG. 4 is a left view of the input/output module; FIG. 5 is a right view of the input/output module; FIG. 6 is a top view of the input/output module; and, FIG. 7 is a bottom view of the input/output module. The broken lines shown represent the portions of the input/output module that form no part of the claimed design.
